[57] **CLAIM**

The ornamental design for a spoke unit for vehicle wheel, as shown and described.

DESCRIPTION

FIG. 1 is a front elevational view of a spoke unit for vehicle wheel showing my new design; and,

FIG. 2 is a side perspective view thereof.

The broken line showing of the rim in FIG. 1 is for illustrative purposes only and forms no part of the claimed design. The broken lines in FIGS. 1 and 2 at the inner edge of the spokes define the inner boundary of the claimed design and form no part thereof.
